No 173

William H. K. Design for a Cookin's Range.
Patented April 1848.

FIG. 1.

Des. 173

William Hickok City of New York
Letters Patent No 173 dated April 14th. 1848

The Schedule referred to in these Letters Patent and
making part of the same.

To all whom it may concern.

I do know that I, William Hickok, of the City, County, and
State of New York, have invented a new Design for a Range-Front
of a Cooking Range, and do hereby declare that the following, is a full
and exact description of the same, reference being had to the annexed
drawings, making part of this Specification.

Figure 1 is an elevation of the front plate of the range
divested of the doors and bottom plate.

Description

The front plate of the Range is divided and laid off
into rectangular or oblong panels of raised work, separated by
mouldings as represented in figure 1. Two of the panels are left open
to be closed by the usual doors. The panels A, B, C, D, of raised work
are foliated and ornamented in basso-relievo, in the manner repre-
sented by the configurations a, b, c, d, e, -

Claim

What I claim as my invention and desire to se-
cure by Letters Patent is the combination and arrangement of the
configurations a, b, c, d, e, in basso-relievo with the panels A,
B, C, D, forming an ornamental front for a cooking-range, as des-
cribed and represented in the annexed drawing.

In testimony whereof I have hereunto signed my name
before two subscribing witnesses, this eighteenth day of March 11, 1848.

Wm. Hickok
Isaac C. Barker

Wm. Hickok.
